UNITED STATES PATENT OFFICE.

WILLIAM F. TOSNEY, OF PHILADELPHIA, PENNSYLVANIA, ASSIGNOR TO UNION
SPECIAL MACHINE COMPANY, OF CHICAGO, ILLINOIS, A CORPORATION OF
ILLINOIS.

COMBINED TRIMMING MECHANISM AND PRESSER-FOOT.

1,286,452.

Specification of Letters Patent. Patented Dec. 3, 1918.

Application filed January 17, 1917. Serial No. 142,387.

To all whom it may concern:

Be it known that I, WILLIAM F. TOSNEY, a citizen of the United States, residing at Philadelphia, in the county of Philadelphia, State of Pennsylvania, have invented certain new and useful Improvements in Combined Trimming Mechanism and Presser-Feet, of which the following is a description, reference being had to the accompanying drawing and to the figures of reference marked thereon.

The invention relates to new and useful improvements in presser feet for sewing machines, and more particularly to a presser foot which is adapted to guide and hold the abutted edges of fabric sections which are to be united by stitching to form a flat seam.

Prior to my invention, a presser foot of the above character has been constructed wherein the foot portion is formed of a main section and an auxiliary section, one of which is yieldingly mounted relative to the other so as to properly hold and guide two fabric sections, one of which is thicker than the other. Such presser foot has also been provided with a slot located between the sections and leading from the front end of the presser foot to a point adjacent the needle opening so that the fabric sections may have their edge portions turned up and trimmed preparatory to the uniting of the same.

An object of my invention is to provide a foot of the above character with means carried by the main section of the foot for supporting the up-turned portions of the fabric sections at each side thereof so as to prevent the same from curling or turning back, thus forming a ridge or rib instead of a flat seam.

In the drawings, which show by way of illustration one embodiment of the invention:

Figure 1 is a side view showing the end of a work support, the needle bar, the needles carried thereby, and the improved presser foot in side elevation;

Fig. 2 is a top plan view of the parts shown in Fig. 1, the needle bar being omitted;

Fig. 3 is a view, partly in section and partly in side elevation, showing my improved presser foot;

Fig. 4 is a bottom plan view of the same;

Fig. 5 is a sectional view on the line 5—5

of Fig. 2, the work support being omitted; 55 and

Fig. 6 is a view showing, more or less diagrammatically, two fabric sections, one of which is thicker than the other, united by stitching. 60

My improved presser foot is constructed for holding and guiding two fabric sections which are to have their edges abutted and united by stitching so as to form a flat seam. The edge portions of the fabric sections are 65 turned up and are led through a slot formed in the presser foot, and extending from the front end of the presser foot substantially in the line of feed to a point adjacent the needle opening in the presser 70 foot. These up-turned edge portions are trimmed, after which they are brought back into the plane of the fabric sections and united by suitable stitching mechanism. The presser foot has a main section and an 75 auxiliary section. The slot is located in the main section and wholly between the side edges thereof so that there is a portion of the main section extending along each side of the up-turned edge portions of the fabric 80 sections. The auxiliary section is yieldingly supported relative to the main section and is adapted to clamp and hold a fabric section of a single thickness, while a fabric section, for example, of double thickness is 85 clamped and held by the main section of the presser foot.

Referring more in detail to the drawings:

The improved presser foot is shown as 90 applied to a sewing machine having a work support 1 and a needle bar 2 carrying two pairs of needles 3—3 and 4—4. The presser foot, as indicated at 5 in the drawings, is mounted on a presser bar 6 and has a rearwardly extending arm 7 which is secured to a guide bar 8. Said presser foot is formed with a main section 9 which is rigidly attached to the shank 10 of the presser foot. This main section has, as herein shown, two 100 needle openings 11 and 12. The needle opening 11 is adapted to receive the front pair of needles 3—3, while the needle opening 12 receives the rear pair of needles 4—4.

The main section of the presser foot is 105 formed with a slot 13. This slot is parallel with the line of feed and is located directly in front of the needle openings. It extends

from the front end of the foot to a point adjacent the front needle opening. The slot is located wholly between the side edges of the main section of the presser foot. Said 5 presser foot is also formed with an auxiliary section 14 which extends alongside of the main section and is substantially of the same length as the main section. This auxiliary section is rigidly attached to the shank 10, 15, which is adapted to slide in a suitable recess formed in the main shank 10 of the presser foot. This shank 15 is held in the recess formed in the main shank of the presser foot therefor by a cover plate 16 20 which is secured to the shank by suitable screws 17. The shank 15 has a vertical slot 18 therein and a stop pin 19 carried by the main shank 10 and extending into said slot limits the up and down movements of the 25 auxiliary section 14 relative to the main section of the presser foot. A spring 20 attached to the main shank of the presser foot by a screw 21 bears on the upper end of the shank 15 and normally tends to force the 30 lower surface of the auxiliary section of the foot into a plane lower than the plane of the lower surface of the main section of the presser foot.

The purpose of this auxiliary section is to 35 clamp and firmly hold the fabric section located at the right of the foot, as viewed in Fig. 5 when the same is of less thickness than the fabric section at the other side of the foot. It sometimes occurs in the forming of 40 garments that the fabric section on one side of the seam is of double thickness while the fabric section on the other side of the seam is of single thickness. In Fig. 5 of the drawings, I have shown such a condition where 45 the material under the main section of the presser foot is indicated at f and f' , while the material under the auxiliary section of the presser foot is of single thickness and is indicated at f^2 . The spring 20 forces the 50 auxiliary section down onto this single thickness of fabric f^2 , while the main foot section rests on the double thickness of the fabric. It will thus be seen that both sections of the fabric will be firmly clamped. 55 My improved presser foot is particularly adapted for the guiding and holding of fabric sections which are to have their edges abutted and joined to form a flat seam. The edge portions of the fabric sections are turned-up as clearly shown in Fig. 5 of the 60 drawings, and led through the slot 13. A trimming mechanism consisting of a stationary blade 22 and a movable blade 23 operates to trim these up-turned edge portions after which they are brought back into the plane of the fabric sections and united by the stitching mechanism.

It will be noted that the slot 13 is located between the side edges of the main section 65 9 of the presser foot and, therefore, there is

a section or finger 9^a at one side of the up-turned edge portions, while there is a section 9^b at the other side of the up-turned edge portions. These up-turned edge portions will, therefore, be guided and held in a vertical position while they are being trimmed, and these sections 9^a and 9^b will also insure that these upturned edge portions, after they are trimmed, are turned back into flat abutted relation, as clearly shown in Fig. 6 of the drawings. In other words, if the finger 9^a were omitted the upturned edge portion of the fabric section underneath the auxiliary section of the presser foot would be free and unguided above this auxiliary section and there would be a tendency of this unguided trimmed upturned edge portion to roll back onto the body portion of the fabric section. The finger 9^a, however, extending along the edge of the upturned fabric section referred to prevents this rolling back and insures that the upturned section will be guided back into the plane of the fabric section. The end wall of the slot guiding the upturned edge sections is smooth and unbroken and, therefore, there is no chance of the edges of the fabric being caught as is the case where the auxiliary section forms one wall of the slot and has a movement relative to the main section.

The finger 9^a is carried by a section 9^c which is formed with the needle openings and this section may be removed and replaced by a new section in case the stitch fingers extending into the needle openings are broken, which avoids the necessity of replacing the entire main section of the presser foot.

It is obvious that minor changes in the details of construction and the arrangement of parts may be made without departing from the spirit of the invention as set forth in the appended claims.

Having thus described the invention, what is claimed as new is:—

1. The combination of horizontally disposed trimming blades, with a presser foot comprising a main foot portion having a needle opening and a slot extending from the front end of the foot to a point in advance of and adjacent the needle opening for guiding upturned edge portions of fabric sections to the trimming blades and an auxiliary yielding foot extending along the side of said main foot portion, said presser foot being constructed so as to support the trimmed edges at both sides thereof regardless of the position of the auxiliary foot portion.

2. The combination of horizontally disposed trimming blades, with a presser foot comprising a main foot portion having a needle opening and a slot extending from the front end of the foot substantially parallel with the line of feed to a point in advance

of and adjacent the needle opening, said slot being located between the side edges of the main portion of the foot and being adapted to guide the upturned edge portions of fabric sections to the trimming blades, and an auxiliary yielding foot extending alongside of the main foot portion.

In testimony whereof, I affix my signature, in the presence of two witnesses.

WILLIAM F. TOSNEY.
